UNITED STATES PATENT OFFICE.

WILLIAM J. WILKES, OF CHICAGO, ILLINOIS.

GRAIN-BINDER.

SPECIFICATION forming part of Letters Patent No. 285,230, dated September 18, 1883.

Application filed March 29, 1883. (No model.)

To all whom it may concern:

Be it known that I, WILLIAM J. WILKES, of Chicago, county of Cook, and State of Illinois, have invented certain new and useful Improvements in Grain-Binders, of which the following is a full, clear, and exact description, that will enable others to understand and make use of the same, reference being had to the accompanying drawings, and to letters of reference marked thereon, forming a part of this specification.

This invention relates to improvements in a tying mechanism for grain-binders; and it consists, first, of means for transmitting motion from the main shaft of the operating mechanism to the cord-clamping disk; second, of means for clamping the cord in relation to the clamping-disk, and finally the arrangement of a knife for severing the binding-cord, all as will be hereinafter more fully set forth.

Figure 1 is a top view of the frame or bracket supporting the tying mechanism embodying my improved features; Fig. 2, a vertical transverse section in the plane 2 2, Fig. 1; and Fig. 25 3, a vertical section in the plane 3 3, Fig. 2.

Referring to the drawings, A represents the frame or bracket supporting the several parts composing the tying mechanism; A', the main shaft of the knotter-operating mechanism, 30 having a bearing in and rotating in the sleeve A², which is an integral part of the tyer-frame; A³, the hub carrying the discharge-arm A⁴. The hub A³ is provided with a projecting collar or sleeve, as indicated by the dotted lines 35 in Fig. 1 of the drawings, which telescopes with the hub B of the segmental gear-wheel B', to which it is adjustably secured by the set-screw a, and rotates simultaneously with the hub A³, carrying the discharge-arm, which is 40 secured to the shaft A' by means of the set-screw a'. The gear-wheel B' has a dish-shaped rim, as shown, and is provided with a segment series of teeth, a², arranged at one point on the inner dished surface of the rim and set 45 at the proper angle to adapt them to engage with the beveled pinion B² located on one end of the diagonal shaft B³. The dish-shaped rim of the gear-wheel serves to retain the pinion B² in proper relative position when not in

engagement with the series of segmental teeth. 50 The connecting-shaft B³ is set at an oblique angle relative to the shaft of the gear-wheel B', and the opposite end of the shaft is provided with the pinion B⁴, adapted to engage with the bevel-gear wheel C placed on the 55 lower end of the short vertical shaft C' and revolves in a horizontal plane. By this arrangement the required motion is transmitted to the cord-holding disk D placed on the upper end of the shaft C'.

The device for clamping the binding-cord at the proper moment consists of the plate C², the rear end of which is fulcrumed at a³ and is secured to the tyer-frame by the adjusting-screw a⁴, as shown in Fig. 2 of the drawings, 60 by which means the tension of the clamping-plate may be conveniently regulated as circumstances may require. The inner edge of the clamping-plate bearing against the collar or enlarged part b of the shaft C' is curved, 65 as indicated by the dotted lines in Fig. 2 of the drawings, to correspond to the circular form of the cord-holding disk D, the binding-twine being clamped between the upper side of the plate and the under side of the disk D. 70 The disk D is rigid on the shaft C' and is provided with four U-shaped notches b' placed at equal distances apart in the periphery of the same. These notches catch and hold the 75 binding-cord as the disk rotates and carry the 80 cord along until it is grasped by the knotting-hooks E.

The back end of the curved cutting-knife F, indicated by dotted lines in Fig. 1 of the drawings, is pivoted to a part of the bracket under 85 the knotting-hooks, while the opposite loose end is bent around and lies flat on top of the disk D. The upper end of the shaft C' is of a square form, having the rounded projecting corners b², which are adapted to be brought 90 successively in contact with the loose end of the knife F and force the same in the opposite direction from that in which the disk D is revolving. The binding-cord is cut at the proper time by the inner curved edge of the knife F 95 at d, and the sharp edges of the notches in the disk D. These cutting-edges move toward each other from opposite directions, produc-

ing a shearing cut. The waste end of the binding-cord, which is left between the notches and underneath the disk D after the binding of each sheaf, is carried along by the rotating disk beyond the point of contact with the clamping-plate, and then drops out of the way by its own weight, thus preventing all danger of these parts from clogging from this cause. By reason of the rounded projecting corners of the upper end of the shaft C' these parts are adapted to have a cam-like action, the knife being thrown forward by frictional contact with the rounded corners in regular order of succession, to meet the binding-cord as it is carried toward the knife by the disk D. The loose end of the knife F is retained in close contact with the upper end of the shaft C' by reason of the frictional contact or bearing on the upper side of the disk D. By means of the gear-wheel B', which is adapted to have an independent adjustment by simply adjusting the set-screw which secures it to the hub A³, the cord-disk D may be accurately set, so as to bring the cord in contact with the cutting-knife at the proper time for severing the same, which is when the knot is completed and cord is strained taut by the knotting-hooks on the one side and the clamping-plate on the other. The construction and operation of the knotting-hooks E, and the mechanism for transmitting motion to the same are not new or original with me; but are the same as shown

in other machines. Therefore a general and detailed description thereof is omitted.

Having thus described my invention, what I claim as new, and desire to secure by Letters Patent, is—

1. In a grain-binder, the combination, with a segmental gear-wheel carried by and adapted to have the described adjustment relative to the main shaft of the knoter mechanism, of the pinion B², adapted to engage with said gear-wheel, the shaft B³, the pinion B⁴, the bevel gear-wheel C, and the shaft C', whereby motion is transmitted to the cord-clamping disk, substantially as described. 40

2. In a grain-binder, the combination, with the cord-clamping disk D, provided with a number of notches in the edge of the same, of 50 the shaft C', the upper end thereof being of a square form provided with rounded projecting corners, and the curved knife F, having one end pivoted to the bracket while the opposite loose end projects over on the top of 55 said disk, and is adapted to have frictional contact with said disk, and to be struck by the rounded corners of said shaft, whereby said knife is intermittently moved forward to meet and sever the binding-cord, which is carried toward the same by the rotating disk D, substantially as described. 60
